CLAIM

The ornamental design for limiter plates, as shown and described.

DESCRIPTION

FIG. 1 is a first perspective view of left-side guide-style limiter plates;

FIG. 2 is a second perspective view thereof;

FIG. 3 is a third perspective view thereof;

FIG. 4 is a fourth perspective view thereof;

FIG. 5 is a left-side elevation view thereof;
FIG. 6 is a right-side elevation view thereof;
FIG. 7 is a front elevation view thereof, the rear elevational view being a mirror image thereof;
FIG. 8 is a top plan view thereof; and
FIG. 9 is a bottom plan view thereof.
FIG. 10 is a first perspective view of right-side guide-style limiter plates;
FIG. 11 is a second perspective view thereof;
FIG. 12 is a third perspective view thereof;
FIG. 13 is a fourth perspective view thereof;
FIG. 14 is a top plan view thereof;
FIG. 15 is a bottom plan view thereof; and
FIG. 16 is a front elevation view thereof, the rear elevational view being a mirror image thereof.
FIG. 17 is a first perspective view of left-side off-centered-style limiter plates;
FIG. 18 is a second perspective view thereof;
FIG. 19 is a third perspective view thereof;
FIG. 20 is a fourth perspective view thereof;
FIG. 21 is a left-side elevation view thereof;

FIG. 22 is a right-side elevation view thereof;
FIG. 23 is a front elevation view thereof, the rear elevational view being a mirror image thereof;
FIG. 24 is a top plan view thereof; and
FIG. 25 is a bottom plan view thereof.
Right-side off-centered-style limiter plates can be a mirror image of the left-side off-centered-style limiter plates.
FIG. 26 is a first perspective view of no-dent-style limiter plates;
FIG. 27 is a second perspective view thereof;
FIG. 28 is a third perspective view thereof;
FIG. 29 is a fourth perspective view thereof;
FIG. 30 is a left-side elevation view thereof;
FIG. 31 is a right-side elevation view thereof;
FIG. 32 is a front elevation view thereof, the rear elevational view being a mirror image thereof;
FIG. 33 is a top plan view thereof; and,
FIG. 34 is a bottom plan view thereof.
Right-side no-dent-style limiter plates can be a mirror image of the left-side off-centered-style limiter plates.
